UNITED STATES PATENT OFFICE.

ARTHUR C. SOULE, OF SAN FRANCISCO, CALIFORNIA.

SASH MOUNTING.

Application filed June 19, 1923. Serial No. 646,340.

To all whom it may concern:

Be it known that I, ARTHUR C. SOULE, a citizen of the United States, and a resident of the city and county of San Francisco, 5 State of California, have made a new and useful invention, to wit, Improvements in Sash Mountings; and I do hereby declare the following to be a full, clear, concise, and exact description of the same.

10 This invention relates particularly to a mounting for supporting and controlling the opening and closing movements of a sash or other analogous enclosures.

An object of the invention is to provide 15 a sash mounting which is simple in construction, easily installed, demounted and adjusted, which will support a sash uniformly in all adjustments and permit the sash to be substantially reversed on its 20 mounting.

A further object of the invention is to provide a sash guiding mechanism for controlling and regulating the opening and closing movement of a swinging sash within 25 a window frame, and having means to increase or diminish the freeness of movement of the moving parts of the sash guiding mechanism.

A still further object of the invention is 30 to provide a window frame having a sash slidably and pivotally related thereto by means of frictionally adjustable supporting arms, connecting the sash and frame, for maintaining the sash in any open position 35 against wind pressure and the like. Other objects and advantages will appear as this description progresses.

In this specification and the annexed drawings, the invention is illustrated in the 40 form considered to be the best, but it is to be understood that the invention is not limited to such form, because it may be embodied in other forms, and it is also to be understood that in and by the claims 45 following the description, it is desired to cover the invention in whatsoever form it may be embodied.

In the accompanying two sheets of drawings,

50 Fig. 1 is a vertical cross-section taken through a window frame having a sash mounted therein in accordance with my invention.

Fig. 2 is a cross-section taken through 55 Fig. 1 on the line 2-2 showing the sash in the closed or vertical position.

Fig. 3 is a section taken through Fig. 1 on the line 3-3, showing the sash in a vertical position within a window frame.

Fig. 4 is a vertical section through a 60 window frame having a sash mounted therein on a modified form of operating apparatus.

Fig. 5 is an enlarged fragmentary cross-section taken through Fig. 4 at the uppermost slide shoe and showing the sash in a 65 closed or vertical position.

Fig. 6 is an enlarged section taken through Fig. 4 on the line 6-6.

Fig. 7 is a still further modified form of 70 construction.

Fig. 8 is a modified form of guide track.

This invention relates to the pivoting of 75 a window sash, on its opposite stiles at a pair of corresponding points, to slide shoes which are slidably retained in a pair of independent and angularly arranged guides on opposite sides of a casement.

In detail, the construction illustrated in 80 the drawings includes a window frame composed of a sill 1, stool 2, and side jambs 3, connected across the top by the lintel 4, together with the usual stops 5, or other weatherproofing finish, mounted on the interior of the jambs, stool and lintel. 85

A sash 6 is adapted to be mounted in the window frame and slidably and pivotally connected at a pair of corresponding points, on each of its opposite stiles, to separate 90 slide members one member of each pair being confined to vertical and the other to horizontal movements on the adjacent side of the window frame.

The side jambs 3, of the frame are either 95 channeled to form guideways, as in Fig. 7, or are provided with metal guideways 7 having flange edges 8 thereon, shown in Figs. 1 through 3, which are adapted to be secured in a relatively vertical position and in alignment with each other, on the opposite side jambs. The flange edges 8 of the channel guideways 7 have holes therein; 100 through which nails or screws may pass for fixedly securing the guideways to the said jambs. The stops 5 are adapted to be secured to the jambs 3, to partially cover the guideways 7 so as to finish the interior of the window frame in accordance with standard practice. The channel guideways 7 are 105 preferably formed from metal of any desirable contour. If desired, the guideway 7 could be provided with means for regulat-

ing friction on the slide shoe by the construction indicated in Fig. 8.

Slide shoes 12, consisting of metal members with flange ends 11 are adapted to be slidably retained on the guideways 7. The flanges 11 project away from the guideways a distance equivalent to the thickness of the edge of the particular sash to be supported. The sash 6, at corresponding points on its opposite side stiles, and adjacent an end thereof, is pivotally connected by the pivots 13 on the sash socket plates 19, to the slide shoes 12. The socket plates 19 are adapted to have the sash 6 installed therein, and to have the fastening screws 20 passed through slots in the socket plates to secure the sash and socket plates together and to permit the obtaining of lateral adjustment of the sash 6 within the window frame. At the upper ends the socket plates 19 are pivoted to the flanges 11, and at the lower ends, the said socket plates are pivoted to the horizontal slide shoes 17, to be hereinafter described in detail. This manner of mounting the opposite stiles of the sash in the socket plates is a convenient and economical method of mounting or demounting the sash for connection to its operating fixtures and eliminates the necessity of having to remove said fixtures from the window frame. The slide shoes 12 support the sash 6 for sliding movement in a vertical direction, and also permit the sash to be swung outwardly from a closed vertical position to a substantially reversed position.

Channel shaped guideways 14 are placed in a substantially horizontal position on both jambs 3 of the window frame. The guideways 14 are preferably placed at right angles to the guideways 7 in order that the paths of sliding movement, in both the horizontal and vertical guides, will cross. The side jambs 3 are grooved out to receive the guideways 14 and to allow the outer faces of the guideways 14 to lie flush with the faces of the jambs 3 and to pass under the vertically positioned guideways 7. Although I have shown and described the vertical and horizontal guideways as separate and independent members, it would be clearly within the purview of the invention to form both guideways, integrally, in one element.

The bent side 16 of the guideway 14 is shaped so that the free edge 16' extends over the channel for a greater distance than the opposite edges of said guideway. Slide shoes 17 are mounted within the guideways 14 and confined therein by the bent edges of said guideways. The slide shoes 17 are connected by the pivots 18 to the lower end of socket plates 19, on opposite stiles of the sash 6, between the head rail and horizontal center of the sash. Screws 21 pass through openings provided in the bent sides 16 of the guideways 14 into the jambs 3 for the pur-

pose of binding the guideways and controlling the ease or freeness with which the shoes 17 will slide in said guideways. The screw 21 by varying the tension placed upon the guideway 14 thus regulates the friction 70 upon the guide shoes 17, and enables the sash to be held open in any desired position against wind pressure or the like.

The sash 6, by means of the vertically 75 slidable shoes 12 and the horizontally slid- 80 able shoes 17, may be thus supported within the window frame and moved from a closed vertical position into a substantially reversed position. The slide shoes 12 retained in the vertical guideways 7 support the sash within 85 the window opening, and additional support is furnished to the sash by the shoes 17 sliding in the horizontal guideways, which sup- 90 port and give an accurate control over the movement of the sash.

In the modified form of sash mounting shown in Figs. 4, 5 and 6, vertically positioned guideways 7' are provided which extend approximately the full length of the sash. The sash 6' is pivotally connected at 90 its upper end by pivots 13' on the plates 23 to the slide shoes 11', slidably mounted on the vertical guideways 7'. Horizontal guideways 14' are mounted at corresponding 95 points on the side jambs 3 in recesses, or grooves, provided in said jambs and the slide shoes 17' are slidably confined in the guide- 100 ways 14'. Sash supporting arms 24 are pivoted at 25 to the plates 25' on the opposite rabbeted stiles of the sash 6', at points in- 105 termediate the head rail 6' of said sash and the horizontal center thereof. The opposite ends of the arms 24 are pivoted at 26 to slide shoes 27 (corresponding to the slide shoes 11') which are mounted for move- 110 ment in a vertical direction on the guide- 115 ways 7'. The arms 24 are pivoted intermediate their ends at 28 to the slide shoes 17' mounted in the horizontal guideways 14'. Screws 20' are adapted to pass through one 110 side of the guideways 14' for creating friction on the slide shoes 17'. The support arms 24 may be effectively used, in conjunction with the slide shoes 17' of the horizontal guideways, for supporting and controlling the opening and closing movements of a sash of a larger size than could be conveniently operated by the mechanism shown in Figs. 1 through 3 inclusive. The arms 24, thus aid the slide shoes 11' in supporting 120 the weight of the sash 6'.

Both of the sash 6 or 6' illustrated in the drawings, when operatively installed in a window frame are opened by manually pushing outwardly on the lower rail of said 125 sash. The outward movement of the lower rail of the sash causes the slide shoes 11 or 11' (on the head rails of the sash) to de- 130 scend. As the upper rail of the sash ap- proaches the horizontal plane, the slide

shoes 17 or 17' in the horizontal guides, move outwardly. The horizontally movable slide shoes 17 or 17' serve to support the weight of the sash in conjunction with the support of the sash controlled by the slide shoes 11 or 11' on the vertical guides. The control of the sash in a window frame by either the preferred or modified forms of construction is identical. The modified form of construction is resorted to where the sash to be supported can not be conveniently manipulated and controlled by the preferred form of sash mounting. A sash mounted in the manner described may be substantially reversed in a window opening so as to present its outer surface to the interior of a room to facilitate washing.

Although I have shown and described a sash mounting with particular reference to a wooden window sash, it is to be understood that it would be clearly within the purview of the invention to utilize the sash mounting on different kinds of windows and transoms. Although I have illustrated and described a vertically positioned sash adapted to operate in a vertical plane it is to be understood the type of sash mounting described could be applied equally as well to a casement window adapted to operate in a horizontal plane.

Having thus described this invention, what I claim and desire to secure by Letters Patent is:

1. A window construction comprising a frame provided with a separate guide on the two opposite sides thereof; a separate slide shoe engaging each guide; a sash, pivotally connected, at corresponding points on its opposite sides to each slide shoe; a separate guide on the two opposite sides of said frame positioned angularly to and intermediate the ends of said first mentioned guides; and a separate slide shoe pivoted to said sash at corresponding points on its opposite sides and slidably related to each last mentioned guide, whereby said sash is rotatable on one side only of said first mentioned guides.

2. A window construction comprising a frame provided with a pair of vertically positioned guides on opposite sides thereof; a pair of guides, positioned at substantially right angles to and intermediate the ends of said first mentioned guides, on opposite sides of said frame; a separate slide shoe engaging each of said guides; and a sash in said frame pivotally connected at a pair of corresponding points on each of its opposite sides to said separate slide shoes.

3. A window construction comprising a frame provided with a separate guide on the two opposite sides thereof; a separate slide shoe engaging each guide; a sash, pivotally connected at corresponding points on its opposite sides to each slide shoe; a separate

guide on the two opposite sides of said frame positioned angularly to said first mentioned guides; a separate slide shoe pivoted to said sash at corresponding points on its opposite sides, and slidably related to said last mentioned guides; and means for regulating said last mentioned guides to control the sliding of the shoes therein.

4. A window construction comprising a frame provided with guides on opposite sides thereof; support guides, positioned at substantially right angles to said first mentioned guides, on opposite sides of said frame; a separate slide shoe engaging each of said guides; a sash in said frame pivotally connected at a pair of corresponding points on each of its opposite sides to said separate slide shoes; and mean for regulating said last mentioned guides to control the sliding of the shoes therein.

5. A window construction comprising a frame provided with vertically positioned guides on opposite sides thereof; horizontally positioned guides on opposite sides of said window frame; a slide shoe engaging each of said vertical and horizontal guides; and a sash in said frame pivotally connected at a pair of corresponding points on its opposite sides to the slide shoes in said vertical and horizontal guides, whereby said sash is rotatably supported and controlled in all opened and closed positions by the slide shoes in both pairs of guides on opposite sides of the window frame.

6. A window construction comprising a frame provided with vertically positioned guides on opposite sides thereof; horizontally positioned guides on opposite sides of said window frame; a slide shoe engaging each of said vertical and horizontal guides; a sash in said frame pivotally connected at a pair of corresponding points on each of its opposite sides to the slide shoes in said vertical and horizontal guides; and means for regulating said horizontal guides to control the sliding of the shoes therein.

7. A window construction comprising a frame, provided with guides on opposite sides thereof; slide shoes engaging said guides; a sash pivotally connected on its opposite sides, to said slide shoes; support guides on opposite sides of said frame related to said first mentioned guides; and slide shoes, pivoted to said sash on its opposite sides, and slidably confined in said support guides, whereby said sash is rotatably supported and controlled in all opened and closed positions by the slide shoes in both pairs of guides on opposite sides of the window frame.

8. A window construction comprising a frame, provided with guides on opposite sides thereof; slide shoes engaging said guides; socket plates pivotally connected to said slide shoes; support guides on oppo-

site sides of said frame related to said first mentioned guides; slide shoes confined in said support guides and pivotally connected to said socket plates; and a sash secured on its opposite sides to said socket plates.

9. A window construction comprising a frame, provided with guides on opposite sides thereof; slide shoes engaging said guides; a sash pivotally connected on its opposite sides, to said slide shoes; support guides positioned on opposite sides of said frame substantially at right angles to said first mentioned guides; slide shoes pivoted to said sash on its opposite sides, and slidably confined in said support guides; and means for regulating said support guides to control the sliding movement of the shoes therein.

10. A window construction comprising a frame, provided with guides on opposite sides thereof; slide shoes engaging said guides; socket plates pivotally connected to said slide shoes; a sash secured on its opposite sides to said socket plates; support guides on opposite sides of said frame related to said first mentioned guides; and slide shoes, pivoted to said socket plates on opposite sides of said sash, and slidably confined in said support guides.

11. A window construction comprising a frame provided with guides on opposite sides thereof; support guides on opposite sides of said window frame related to said first mentioned guides; a slide shoe engaging each of said guides; a sash in said frame pivotally connected at a pair of corresponding points on each of its opposite sides to the slide shoes in each of said guides; and

means to control the sliding movement of said slide shoes in said guides, whereby said sash is rotatably supported and controlled in all opened and closed positions by the slide shoes in both pairs of guides on opposite sides of the window frame.

12. A reversible window construction comprising a frame provided with guides on opposite sides thereof; support guides, positioned at substantially right angles to said first mentioned guides, on opposite sides of said frame; an independent slide shoe engaging each of said guides; a sash in said frame pivotally connected at a pair of corresponding points on each of its opposite sides to each of said slide shoes.

13. A window construction comprising a frame; a sash in said frame; means to support said sash in a reversible position in said frame comprising, a coacting slide member and guide secured between each side of said sash and frame at corresponding points on the two opposite sides thereof, and a coacting slide member and guide secured between each side of said sash and frame at corresponding points on the two opposite sides thereof at an angle to each of said first mentioned guides, so that each of said first mentioned slide members will move in a different direction than said last mentioned slide members.

In testimony whereof, I have hereunto set my hand at San Francisco, California, this 13th day of June 1923.

ARTHUR C. SOULE.

In presence of—
LINCOLN V. JOHNSON.
